UNITED STATES PATENT OFFICE.

JOSEPH CARMEL, OF NEW YORK, N. Y., ASSIGNOR TO FRANK M. ASHLEY, OF NEW YORK, N. Y.

KEY HOLDER.

Application filed March 24, 1921. Serial No. 455,258.

To all whom it may concern:

Be it known that JOSEPH CARMEL, citizen of Poland, and resident of the city of New York, in the county of Kings and State of New York, has invented certain new and useful Improvements in Key Holders, of which the following is a specification.

This invention relates to key holders and the object of my invention is to provide means for holding keys in such a manner as to be easily removable therefrom and means for enclosing the holder together with the keys.

The novel features of my invention will be particularly set forth in the claims forming part of this specification.

Referring to the drawings,

Fig. 1 is a perspective view of a key holder and cover embodying my invention, the cover portion being partly broken away for the purpose of illustration;

Fig. 2 is a perspective view showing the key holder attached to the outer wall of a pocket book under the flap;

Fig. 3 is a cross-sectional view on a larger scale taken on line 3—3 of Fig. 2; and

Fig. 4 is a view of the metal portion of a holder as first stamped from a sheet.

A indicates a thin sheet of metal formed with V-shaped projections A'—A', etc., adapted to pass through the material of which the cover B is made and be bent over and clinched thereon as illustrated at B'—B', etc. The projecting arms C—C, etc., are bent upward to form hooks as illustrated in Figs. 1, 2 and 3 and the upper end is curved outwardly at C' just above the point of contact with the downwardly extending arm D to permit a key to be easily guided into the hook. The arms D—D, etc., are formed from metal pressed from the body of the sheet and offset therefrom as clearly illustrated in Figs. 1 and 3, and the ends D' are bent inwardly toward the face of the plate A to permit the head E of a key to force the contacting ends C' and D' apart in the act of removing a key from the hook of the holder. The arms and hooks are resilient and are sprung apart in the act of removing a key from the holder.

The cover is open on its lower side K to permit long keys to extend below the edge and may be made of leather or other suitable material and formed as illustrated in Fig. 1 comprising a rectangular sheet F folded to

inclose the key holder, and the adjacent ends held together by a snap-button G. I also provide a back-strip H to which the cover F is attached by cement or other suitable means and the back-strip is provided with fasteners I—I—I—I by means of which the cover F may be secured to the inner side of a suit case or trunk.

In Fig. 2 the flap J serves to cover the metal hooks and keys and by carrying the key-holder attached to the pocket-book the person will not forget the keys when leaving home or office, and will not be liable to misplace or lose them.

Having thus described my invention, I claim as new and desire to secure by Letters Patent:—

1. A key-holder comprising a sheet of metal having arms offset from the sheet and upwardly extending hooks contacting said arms and adapted to hold a key.

2. A key-holder comprising a sheet of metal having arms offset from the sheet and upwardly extending resilient hooks contacting said arms and adapted to hold a key.

3. A key-holder comprising a sheet of metal having resilient arms offset from the sheet and upwardly extending hooks contacting said arms and adapted to hold a key.

4. A key-holder comprising a sheet of metal having arms formed integral offset from the sheet and upwardly extending hooks contacting said arms and adapted to hold a key.

5. A key-holder comprising a sheet of metal having resilient arms formed integral and offset from the sheet and upwardly extending resilient hooks formed integral and contacting said arms to provide a number of closed loops.

6. A key-holder comprising a sheet of metal having resilient arms formed integral and offset from the sheet and upwardly extending resilient hooks formed integral and contacting said arms to provide a number of closed loops, the ends of the arms and hooks being curved in opposite directions.

7. A key-holder comprising a sheet of metal having arms offset from the sheet and upwardly extending hooks contacting said arms and adapted to hold a key, said sheet having means formed integral therewith for connecting the sheet to a cover.

8. A key-holder comprising a sheet of

metal having resilient arms formed integral and offset from the sheet and upwardly extending resilient hooks formed integral and contacting said arms to provide a number of closed loops, the ends of the arms and hooks being curved in opposite directions, and a back-strip having fastening means thereon.

9. A key holder comprising a metal strip

having an arm offset from the strip and an upwardly extending hook contacting said arm and adapted to hold a key.

Signed at New York city, in the county of New York and State of New York, this 29th day of January.

JOSEPH CARMEL.

Witness:

FRANK M. ASHLEY.
